Patented June 7, 1921.

FIG. 5

INVENTOR
Bruce Edward Bliss

BY
H. G. Charles
ATTORNEY

UNITED STATES PATENT OFFICE.

BRUCE E. BLISS, OF WICHITA, KANSAS.

ANTISKID AND MUD-CHAINS.

1,380,522.

Specification of Letters Patent. Patented June 7, 1921.

Application filed August 31, 1920. Serial No. 407,092.

To all whom it may concern:

Be it known that I, BRUCE E. BLISS, a citizen of the United States, and resident of Wichita, in the county of Sedgwick and, 5 State of Kansas, have invented certain new and useful Improvements in Antiskids and Mud-Chains, of which the following is a specification.

This invention relates to an attachment 10 for pneumatic-tired wheels which attachment is designed to function either as an anti-skid when on pavements, or as a traction-maker when the vehicle is stalled in mud or sand. Briefly stated, the device 15 consists of a pair of segmental, rigid attachment-bars, a plurality of transverse chains connecting such bars, and the fastening means hereinafter described.

The object of the invention is to provide 20 a device of the character named which is easily and quickly attachable to a vehicle-wheel without the use of snap-hooks or any other minute or troublesome device, and which is attachable to the upper portion of 25 the wheel by a person standing on the running-board or step of the vehicle. A special advantage of this feature is that the device may be applied after the car has been stalled in mud or sand. Moreover, when 30 intended for use on hard smooth wet pavement, it is obvious that my device is more easily placed and removed than are the well known annular chains sold for the purpose.

A preferred embodiment of the invention 35 is shown by the accompanying drawings, in which:—

Figure 1 is a side elevation of one unit in fastened position upon a portion of a tire and its rim; Fig. 2 is a transverse section on line II—II of Fig. 1, indicating 40 three successive preliminary positions of the lever-fastener in dotted lines; Fig. 3 is an inside plan view of the unit in final position; Fig. 4 is an enlarged detail view of a 45 portion of the lever-fastener. Fig. 5 is a detail view of a modification wherein a hook may be cast upon the side-bar 1 in lieu of an eye, such hook being adapted to be closed upon a link as indicated in dotted 50 lines.

The inner face of each of the rigid bars 1 is flat; the outer face of each bar is cast with a continuous stiffening rib 2. A series of spaced eyes 3 are cast on the convex 55 edge or rib of each bar 1. Each eye 3 receives a terminal link of a chain 4, the two

bars being thus connected by a series of transverse chains.

In each bar 1 is a central perforation 5 for attachment of the fastening members to 60 be described. One fastening member consists of a short heavy chain 6, linked in eye 5 of one bar 1. To the other end of this chain is linked an eyebolt 7 on which is a wingnut 8. Eyebolt 7 passes loosely 65 through a hole in one end of a rigid rim-plate 9—10, which is provided with a pair of flanges 12, adapted to engage the sides of a felly 13 as shown. Plate 9—10 is extended longitudinally in both directions, 70 its extensions 10 affording larger bearing-surface upon the felly. The entire inner face of said plate and its flanges 12 is provided with a thick leather lining 14.

The side of plate 9 opposite eyebolt 7 is 75 formed with a lug 15 in which are formed a concavity shown on Fig. 2 of the drawing, a small interior catch 17, and an exterior catch 18.

Connected to the central eye 5 of one 80 attachment-bar 1, is an eyebolt 19—20 made in two parts, the part 20 being threaded into the part 19, whereby the length of the bolt as a whole is adjustable. Eye 21 on part 20 is connected by a link 22 to an eye 85 23 on one end of a rectangular link 24, through the outer end of which passes a fulcrum-pin 25, on which is rockably mounted the lever-fastener 26. By this term I mean a combined lever and fastener, 90 and not a fastener for a lever. This fastener comprises a lever or handle 26, a heavy lug 27 provided with a shoulder 28, and a smaller lug 29 formed with a shoulder 30.

Rim-plate 9 is formed with a raised rib 31 at each side of lever 26, to guide said lever laterally, or rather to form a more fixed seat for same when closed.

To attach or mount one unit upon a 100 wheel the procedure is substantially as follows: After the rim-plate 9 has been positioned upon the felly 13 as shown in the drawings, the operator grasps the lever handle 26 and engages its shoulder 30 with 105 the outer shoulder 18, which forms a fulcrum. If the reach is too long or too short, adjustment is easily made by turning the screw 20 (with its attached parts). Continuing the closing motion of the lever 26, 110 its large lug 27 enters the concave 16 in lug 15 of plate 9, its shoulder 28 engages

catch 17, forming a second fulcrum for the lever, which is then forced in toward the rim-plate 9 until it bears thereon; the pivot-pin 25 thus being carried in to a point where the tension thereon holds the lever-fastener in closed position.

If the parts are found not to be sufficiently tight upon the tire, the tension may be increased by adjusting the two-part eye-bolt 19-20 which acts like a turnbuckle.

The end of the handle 26 in closed position is so close to the wingnut 8 that the latter can turn backward only slightly, its further rotation being prevented by one of its wings impinging on the end of said handle. Thus, the loosening or loss of the wingnut is automatically prevented.

After one unit has been mounted on a wheel, it is obvious that the wheel may be turned and that one or more additional units of my device be attached in like manner to other segments of the wheel.

The attachment-bars 1 may be made in various lengths without any departure from the construction herein described, though of course the number of cross-chains in a unit may vary.

Having thus described the invention, what I claim, and desire to secure by Letters Patent, is:

In combination in a device of the kind described, a rim-plate, a lever contacting said plate, fastening means tensioning the lever against said plate, other fastening means comprising a bolt passing freely through a hole in the rim-plate, and a wing-nut on said bolt at the outer face of said plate: the free end of said lever being positioned so as to provide a latch to prevent full rotation of said wing-nut.

BRUCE E. BLISS.
